UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

SHOVELING MACHINE.

Application filed February 27, 1924. Serial No. 695,480.

To all whom it may concern:

Be it known that I, PAUL BURKE, a citizen of the United States of America, and resident of Green Bay, in the county of 5 Brown and State of Wisconsin, have invented new and useful Improvements in Shoveling Machines, of which the following is a description, reference being had to the accompanying drawings, which are a 10 part of this specification.

The invention relates to shoveling machines.

In shoveling machines in which the dipper and its handle or stick are mounted to 15 swing and shift relative to its supporting boom, it is sometimes necessary and highly desirable to hoist the dipper when the stick is in an extended position so that the contents of the dipper may be deposited at the 20 desired point. In machines of this general type a dipper stick of reasonable length can be thrust out when about in horizontal position, but hoisting from then on will gradually retract the dipper and stick until finally 25 the sheave associated with the dipper meets the sheave at the outer end of the boom so that some means are necessary to hold the stick in extended position. It has heretofore been quite common practice in some 30 designs of shovels of this general type to use a brake controlled by the operator, either by hand or by foot, to prevent the retraction of the extended stick, but such constructions put an additional duty on the operator 35 and complicate the control mechanism. The object of this invention is to provide automatically operating means whereby the stick once thrust out at or near its limit is prevented from moving inwardly during hoisting, such means operating without complicating the control, as by additional levers, and without adding to the duties of the 40 operator.

A further object of the invention is to 45 provide means whereby dipper sticks substantially longer than the distance between the shipper shaft and the point of the boom may be successfully hoisted in the extended position without complicating the controls.

50 A further object of the invention is to associate an automatic brake with the dipper-operating mechanism so that the brake is automatically released or stays released during the outward movement of the stick; 55 is automatically applied when forces, other

than the retracting means proper, are acting to shift the stick inward; and is automatically released when the stick is retracted.

A further and more particular object of the invention is to provide a shovel of the 60 rope-thrusting type in which the tension of the inward thrusting line is utilized to effect the release of an automatic brake so arranged as to restrain inward translation of the stick except when such tension is 65 applied.

The invention further consists in the several features hereinafter set forth and more particularly defined by claims at the conclusion hereof.

In the drawings: Fig. 1 is a side elevation view of an excavating shovel embodying the invention; Fig. 2 is a detail sectional view on the line 2—2 of Fig. 1; Fig. 3 is a detail sectional view on the line 3—3 of 75 Fig. 1; Fig. 4 is a plan view of the shovel, parts being shown in section.

In the drawings the numeral 5 designates the boom, which may be of any suitable construction, vertically pivotally attached at 80 its lower end to the rotating base 6 of the machine, which base is of well known construction. A hoisting drum 7 and an auxiliary drum 8 are mounted on the base 6 in any suitable manner and driven from the prime mover (not shown) on the base. The drums 7 and 8 may be of any well known construction equipped with clutches and brakes to control their operation. The boom is adapted to be raised and lowered 85 and held in various positions of vertical adjustment by any well known means, such as cables 9 connecting pulleys 10 at the outer end of the boom to parts on the rotating base. The boom shown is of the plate girder type with the dipper handle 11 working between its sides.

A shipper shaft 12 is secured in a support 13 on the boom and the saddle blocks 14 are loose on said shaft. The dipper handle shown is made in two sections and each section has a metal facing 15 which slides in between the parts forming the saddle block. A drum or sheave 16 and sheaves 17 and 18 are loose on said shaft and preferably disposed between the inner parts of the saddle blocks. The dipper or shovel 19 may be of any suitable construction and is mounted, as usual, at the lower end of the dipper handle.

A hoisting cable 20 dead-ended on the 110

drum 7 passes therefrom over a sheave 21 on a shaft 22 at the outer end of the boom, then around a transversely disposed padlock sheave 23 pivotally mounted on the dipper 5 and around the larger part of a compound drum 24 on which it is dead-ended. A cable 25 is dead-ended on the small side 26 of the compound drum 24 and passes one or more times around the drum 16 on the shaft 10 12 and is dead-ended at 27 near the upper end of the dipper stick or handle 11. A cable 28 secured to and wound upon the drum 8 passes over the sheave 17 on the shaft 12, thence over a sheave 29 on the lower end 15 of the dipper stick and thence over the sheave 16 on the shaft 12 and to a brake-operating means hereinafter described which acts as an anchorage for said cable.

With the construction above described, 20 when the drum 8 is prevented from turning by its brake, thereby holding the line or cable 28, and the line 20 is pulled in, the dipper moves approximately in the arc of a circle of which the shipper shaft is the 25 center. If it is desired to crowd into the material being excavated, or to move the dipper farther out, as in loading a wagon, braking effect on line 28 is released slightly, allowing the line 20, pulling on the large 30 side of drum 24, to put a pull, here greater than hoisting effect because of the compound drum, on line 25 which then forces the dipper stick outward. Conversely, if it is desired to move the dipper farther in, hoisting 35 with line 28 produces this effect. While the compound or differential drum is preferred, it is to be understood that the invention is not to be limited the eto unless specifically mentioned. Thus, by a proper manipulation of the lines 28 and 20 any desired 40 swinging and thrusting movement of the dipper and its stick may be effected. Furthermore, since the line 25 which effects the thrust is actuated by the hoist, a crowding 45 effect equal to the full driving force of the engine is secured. With this and other constructions, however, when the stick is in an extended position and hoisting has been continued until the stick is approaching, at, or 50 above the horizontal position, the hoisting cable 20 and other forces, such as the weight of the dipper and its contents, tends to shift the stick inwardly.

To restrain the inward shifting movement 55 of the dipper handle, I form a part of the drum 24 as a brake drum 30 adapted to be engaged by a brake-band 31. One end 31' of this band is adjustably secured to one arm of a bell crank lever 32 loose on a shaft 33 60 fixed on the boom and at a greater distance from the center of said shaft than the point at which the other end of the band is secured to the other arm of said bell crank lever thereby providing an automatic brake which, 65 when the drum 24 rotates in a clockwise di-

rection, as in outward shifting of the dipper handle, acts to automatically release said band and in a counterclockwise direction it acts to tighten said band about the drum 30. An arm 34 is also formed as a part of the 70 lever 32 and a spring 35, secured at one end to said arm and at its other end to the boom, acts to put an initial tension in said band. As the inward shifting tendency of the stick when in an extended position acts through 75 the cable 25 to rotate the drum 24 in a counterclockwise direction, it will be noted that under these conditions the restraining torque of the brake is applied directly to the compound drum 24 and is transmitted 80 through the cable 25 to the dipper handle to hold the same.

In order to release the automatic brake when it is desired to shift the dipper handle inwardly, the retracting cable 28 is secured 85 at its outer end to a lever 36 pivotally mounted intermediate its ends on the support 13 and pivotally connected at its other end to one end of a reach rod or link 36' which is pivotally connected at its other end 90 to the arm 34, whereby the tension produced by the inward pull of the cable 28 will, through the lever 36, link 36' and arm 34, shift said bell crank lever 32 so that its longer arm swings toward the shaft 22 and 95 thereby releases the brake so that the brake is automatically released incident to the operator shifting the dipper stick inwardly and hence no additional control mechanism has to be operated by the operator. A stop 100 37 limits the swing of the lever 36 on release.

From the foregoing description it will be noted that I have provided means which automatically restrains the dipper stick from moving inwardly when it is desired to hold the dipper stick extended, but which permits the dipper stick to be moved outwardly for the digging operations, and which automatically releases without any special operation on the part of the operator when it is 105 desired to retract the stick.

I desire it to be understood that this invention is not to be limited to any specific form or arrangement of parts except in so far as such limitations are included in the 110 claims.

What I claim as my invention is:

1. In a power shovel, the combination of a boom, a dipper and dipper handle mounted thereon for swinging and shifting movements, means including a thrust cable for shifting said handle outwardly, a dipper-hoisting cable, a drum having portions of different diameters connected respectively with said hoisting cable and said thrust cable 120 whereby the working tension in said hoisting cable is utilized to shift said dipper handle, a brake for said drum to hold it against turning movement in a direction preventing inward shifting movement of said dipper 125 130

handle, means for shifting said dipper handle inwardly, and means operated by said inward shifting means to release said brake.

2. In a power shovel, the combination of a boom, a dipper and dipper handle mounted thereon for swinging and shifting movements, means including a thrust cable for shifting said handle in one direction, means including a thrust cable for shifting said handle in another direction, a dipper-hoisting cable, a drum having portions of different diameters connected respectively with said hoisting-cable and one of said thrust cables whereby the working tension in said hoisting cable is utilized to shift said dipper handle, a brake associated with said drum to hold it against turning movement in one direction to prevent shifting movement of the stick in that direction, and means operatively connected with one of said thrust cables and controlled thereby for releasing said brake.

3. In a power shovel, the combination of a boom, a compound drum mounted thereon, a dipper and dipper handle mounted on said boom for swinging and shifting movements, a dipper-hoisting cable connected with the larger part of said drum, a second cable connected with the smaller part of said drum and operatively connected with the dipper handle to shift said handle outwardly, means including a third cable operatively connected with said dipper handle for shifting said handle inwardly, a brake for said drum to hold it against rotation in one direction to prevent inward shifting movement of said handle, and means operatively connected with said third cable and controlled thereby for releasing said holding means.

4. In an excavating machine, the combination with a boom, of a dipper and dipper handle mounted thereon to swing and shift with respect thereto, means for hoisting said dipper and thrusting it outwardly including a drum at the outer end portion of the boom, an automatic brake for restraining said drum against turning movement in one direction to thereby prevent inward shifting movement of the dipper handle, means for shifting the dipper handle inwardly, and means operated by said shifting means to release said brake.

5. In an excavating machine, the combination with a boom, of a dipper and dipper handle mounted thereon to swing and shift

with respect thereto, a drum on the outer end portion of the boom, dipper-hoisting and outward-thrusting means for the dipper associated with said drum, an automatic brake for restraining said drum against turning in one direction to thereby prevent inward shifting movement of the dipper handle, a cable for shifting the dipper handle inwardly, and means actuated by said cable to release said brake.

6. In an excavating machine, the combination with a boom, of a dipper and dipper handle mounted thereon to swing and shift with respect thereto, means for hoisting said dipper and thrusting it outwardly including a drum at the outer end portion of the boom, a brake on said drum whereby to restrain its turning movement in one direction and thereby prevent inward shifting movement of the dipper handle, a shaft adjacent said handle, sheaves on said shaft, a sheave on the lower end portion of the dipper handle, brake-releasing means, and a retracting cable passing over one of said sheaves on said shaft, around the sheave on said dipper handle, over the other sheave on said shaft and dead-ended on said brake-releasing means whereby said releasing means operates to release said brake when said cable is actuated to retract said handle.

7. In an excavating machine, the combination of a boom, a compound drum mounted on the outer end portion thereof, a shipper shaft, a dipper and dipper handle mounted on said shaft to swing and shift relative to the boom, a dipper-hoisting cable connected with the larger part of said drum, a second cable connected with the smaller part of said drum and operatively connected with the dipper handle to shift said handle outwardly, a brake operating on said drum to restrain its turning movement and thereby prevent inward shifting movement of the dipper handle, brake-releasing means, spaced sheaves on said shaft, a sheave on the lower end portion of the dipper handle, a third cable passing over one of said sheaves on said shaft, over the sheave on said handle and over the other sheave on said shaft and dead-ended on said brake-releasing means whereby said releasing means operates to release said brake when said cable is actuated to retract said handle.

In testimony whereof I affix my signature.

PAUL BURKE.
